UNITED STATES PATENT OFFICE.

JOHN ALLISON, OF DRAVOSBURG, PENNSYLVANIA, ASSIGNOR TO PITTSBURGH STEEL FOUNDRY COMPANY, A CORPORATION OF PENNSYLVANIA.

RAILWAY-CAR UNDERFRAME.

1,368,680.

Specification of Letters Patent. Patented Feb. 15, 1921.

Application filed January 30, 1920. Serial No. 355,232.

To all whom it may concern:

Be it known that I, JOHN ALLISON, a citizen of the United States, and a resident of Dravosburg, in the county of Allegheny and 5 State of Pennsylvania, have invented a new and useful Improvement in Railway-Car Underframes, of which the following is a specification.

This invention relates to railway car underframes, and more particularly to the 10 draft rigging device and connection of the same to the body bolster and car sills. The object of the invention is to provide a construction in which the draft sills and the 15 center sills between the body bolster are in the same horizontal plane and connected together to provide a continuous column to resist draft and buffing stresses in practically a straight line and in which the stresses 20 in both directions are transferred to the body bolster.

In the accompanying drawings Figure 1 is a plan view of the end portion of an underframe embodying the invention; Fig. 2 25 is a central vertical longitudinal section therethrough; Fig. 3 is a transverse section on the line 3—3, Fig. 1; Fig. 4 is a plan view of the center connecting member; Fig. 5 is a transverse section on the line 5—5, 30 Fig. 4; and Figs. 6 and 7 are respectively longitudinal sectional and plan views showing a modification.

In the drawings 1 indicates the center sills consisting of two rolled channel beams 35 placed parallel with their webs vertical and flanges projecting outwardly, and connected by the top cover plate 2. This sill extends continuously between the two body bolsters. The body bolster 4 illustrated is of the Sim- 40 plex type, having continuous top and bottom plates 5 and 6 united by vertical web portions 7 of flanged shape and tapering from the center sills toward their ends.

The draft beams 12 are shown as steel 45 castings, having vertical webs and top flanges 14 and bottom flanges 15, and provided with lugs 16 for the follower plates of the draft rigging, and their outer ends provided with seats 17 for supporting the 50 end sill and buffer block, which are shown as of wooden construction. The particular underframe illustrated is for supporting a floor on longitudinal stringers, such as is used in box and similar cars, and in which 55 the sills and stringers are supported inter-

mediate their ends by truss rods. This is only one form to which the invention is applicable.

The draft beams 12 lie in the same horizontal plane as the channel center sills 1, and both the draft beams and center sills abut against the bolster and are of the same vertical height as the bolster. The draft sills are connected to the bolster and to the center sills at the top by means of the cover plate 2 which is extended across the top of the bolster and is riveted through the top cover plate and top flanges of the web members of the bolster by rivets 18 and extends beyond the bolster and overlaps and is riveted to the top flanges 14 of the draft sills by means of rivets 19. At the bottom the draft beams are connected to the center sills and bolster by a special casting which may also form the center bearing plate. As 75 shown in Figs. 1 to 5 the casting has a portion forming the center plate 22 and has portions 23 projecting forwardly and rearwardly thereof, said projecting portions being provided with horizontal flanges 24 which are connected by means of rivets 25 to the bottom flanges 15 of the draft sills and the bottom flanges of the center sills 1, and also with vertical flanges 26 and 27 which are connected respectively by rivets 85 28 to the webs of the draft sills and the webs of the center sills.

This forms a very secure connection and provides a rigid structure in which the draft sills are practically continuations of the center sills and lie in the same plane therewith, so that all tugging and buffing stresses are exerted in a straight line from end to end of the car. Furthermore the inner ends of the vertical flanges 26 on this connecting member abut against the forward and rear edges of the bolster. As a consequence the buffing stresses in both directions are transferred to the body bolster and exert no material shearing stress upon the connecting 95 rivets. The result is that this underframe structure is able to resist to a maximum the stresses which are exerted upon the draft members, and transfers said stresses directly to the body bolster and largely relieves the 100 connecting rivets. Consequently there is less danger of failure than with the ordinary car underframe structures.

Figs. 6 and 7 show a modification in which the bottom connecting plate 23 is provided 110

with an opening 22^a large enough to fit over the center bearing plate 22^b; thus allowing of the use of special or standard center bearing plates.

5 I claim:

1. In a car underframe, the combination of a body bolster, center sills, draft sills, and an integral bottom connecting member having upwardly projecting longitudinal 10 flanges forwardly and rearwardly of the body bolster and abutting the same, said flanges being secured to the central sills and draft sills respectively.

2. In a car underframe, the combination 15 of a body bolster, center sills, draft sills, and an integral bottom connecting member forming a center bearing plate and having upwardly projecting longitudinal flanges forwardly and rearwardly of the body bolster and abutting the same, said flanges being secured to the center sills and draft sills respectively.

3. In a car underframe, the combination 25 of a body bolster, rolled flanged center sills, flanged draft sills, and an integral bottom connecting member provided forwardly and rearwardly of the body bolster with longitudinal horizontal and vertical flanges, the horizontal flanges being connected to the 30 bottom flanges of the center sills and draft sills respectively and the vertical flanges abutting the body bolster and connected to

the webs of the center sills and draft sills respectively.

4. In a car underframe, the combination 35 of a body bolster, flanged center sills, flanged draft sills, and an integral bottom connecting member forming a center bearing plate and provided forwardly and rearwardly of the body bolster with longitudinal horizontal 40 and vertical flanges, the horizontal flanges being connected to the bottom flanges of the center sills and draft sills respectively, and the vertical flanges abutting the body bolster and being connected to the webs 45 of the center sills and draft sills respectively.

5. In a car underframe, the combination 50 of a body bolster, flanged center sills, flanged draft sills, all lying in the same horizontal plane, a cover plate for the center sills extending across the body bolster and overlapping the ends of the draft sills and connected to each, and an integral bottom connecting member having upwardly projecting horizontal flanges forwardly and rearwardly of the body bolster and abutting the same, said flanges being secured to the center sills and draft sills respectively.

In testimony whereof, I have hereunto set 60 my hand.

JOHN ALLISON.

Witness:

V. E. GRIFFIN.
